Primary Examiner — Richard Kearney*Assistant Examiner* — Benjamin M Weeks(74) *Attorney, Agent, or Firm* — Sand, Sebolt & Wernow Co., LPA(57) **CLAIM**

The ornamental design for an easel bracket as shown and described.

DESCRIPTION

FIG. 1 is a perspective view of an easel bracket in accordance with our design;

FIG. 2 is a front elevation view thereof;

FIG. 3 is a rear elevation view thereof;

FIG. 4 is a first side elevation view thereof;

FIG. 5 is a second side elevation view thereof;

FIG. 6 is a first end elevation view thereof; and,

FIG. 7 is a second end elevation view thereof.

The broken lines in the figures illustrate portions of the easel bracket which form no part of the claimed design.
